(57) **CLAIM**

A container liquid catch ring, as shown and described.

DESCRIPTION

FIG. 1 is a top perspective view of the container liquid catch ring;

FIG. 2 is a bottom perspective view of the container liquid catch ring;

FIG. 3 is a top view of the container liquid catch ring;

FIG. 4 is a bottom view of the container liquid catch ring;

FIG. 5 is a side view of the container liquid catch ring;

FIG. 6 is another side view of the container liquid catch ring, rotated 90 degrees relative to the side view depicted in FIG. 5; and,

FIG. 7 is a side view of the container liquid catch ring, with the container liquid catch ring placed on a can in typical application of the container liquid catch ring.

FIGS. 1-7 include broken line depictions of wall spacers and a wall rim and FIG. 7 includes a broken line depiction of a can, which wall spacers, wall rim and can do not form a part of the claimed design.
